[57] ABSTRACT

This invention is directed to the contact interchange of thermal and kinetic energy between adjacent compressible fluid streams across a virtual heat transfer surface at substantially different velocities in parallel flow. The invention may find especial application as a regenerative heat exchanger in gas turbine power plants, or as the low-velocity contact-type air pre-heater of a steam generator or furnace.

Hot low-pressure exhaust fluids and cool compressed intake fluids enter the receiver-side section of an elongate heat exchanger. Intake-fluid stream pressure energy is converted to kinetic energy within nozzle passageways of the receiver-side section. The cold high-velocity intake-fluid stream is rapidly heated in the velocity-accelerated contact interchange process by the hot low-velocity exhaust-fluid stream within the mixing section. Following the contact interchange process, the intake-fluid and exhaust-fluid streams are separated from each other by flow-dividing members and discharged from the separator-side section. Within the preheated intake-fluid stream, normal shock in supersonic flow across the inlet of the intake-fluid discharge passage is averted by the effects of variable control over characteristic length and exhaust-fluid outlet flow control.

COMPRESSIBLE FLUID CONTACT HEAT EXCHANGER

The present invention is a continuation-in-part of my presently pending application Ser. No. 830,189, entitled "Compressible Fluid Contact Heat Exchanger" filed May 19, 1969, now abandoned; my prior application Ser. No. 689,241 entitled "Compressible Fluid Contact Heat Exchanger" filed Nov. 29, 1967, now abandoned; my prior application Ser. No. 632,122 entitled "Compressible Fluid Contact Heat Exchanger" filed Feb. 6, 1967, now abandoned; my prior application Ser. No. 562,068 entitled "Compressible Fluid Contact Heat Exchanger" filed June 1, 1966, now abandoned; and my prior application Ser. No. 323,499 entitled "Compressible Fluid Contact Heat Exchanger" filed Nov. 13, 1963, now abandoned.

This invention relates to the contact interchange of thermal energy between adjacent streams of compressible fluids at different velocities in parallel flow by means of opposed sonic or super-sonic nozzle-diffuser combinations and arrangements, the entire nozzle-diffuser assemblage being concentrically mounted within the confines of a duct or tubular accommodating and mixing chamber.

As used hereinafter,

The term "fluid" shall refer to any liquid or gaseous medium;

The term 'compressible fluid' shall refer to any gaseous medium;

the term 'exhaust fluid' shall refer to the discharge stream of combusted gases from an internal combustion engine, to the exhaust gases from any other heat engine, or to high-temperature gases leaving a combustion chamber or other heat source;

the term 'intake fluid' shall relate to the incoming fluid stream of precombustion gases to an internal combustion engine (air), the incoming fluid stream to a heat engine, the incoming fluid stream to the combustion chamber of any heat exchange apparatus, or to the incoming fluid stream to any other heat source before major quantities of thermal energy are added to the incoming fluid stream;

the term 'heat engine' shall refer to a thermodynamic engine which may convert thermal or molecular energy in the working fluid stream to mechanical energy, or convert mechanical energy to thermal or molecular energy in the working fluid stream;

the term 'contact interchange' shall relate to the fluid-to-fluid exchange of thermal and kinetic energy between adjacent fluid streams having different velocities in parallel flow, and having now physical or mechanical separation between them;

the term 'heating fluid' shall refer to the low-temperature member of adjacent fluid streams in parallel flow which is being heated by contact interchange with an adjacent high-temperature fluid stream;

the term 'cooling fluid' shall relate to the high-temperature member of adjacent fluid streams which is being cooled by contact interchange with an adjacent low-temperature fluid stream;

the term 'combusted fluid' shall refer to a fluid stream within which a combustion process has taken place following the injection of a combustible fuel;

the term 'sub-sonic flow' shall refer to fluid velocities which are less than the velocity of sound in the fluid at a particular energy state;

the term 'sonic flow' shall refer to fluid velocities which are equal to the velocity of sound in the fluid at a particular energy state;

the term 'super-sonic flow' shall refer to fluid velocities which are greater than the velocity of sound in the fluid at a particular energy state;

the term 'mixing length' shall refer to the effective linear dimension perpendicular to the direction of mean fluid flow within which contact interchange of thermal and kinetic energy shall take place between a heating fluid stream and a cooling fluid stream;

the term 'characteristic length' shall refer to the effective linear dimension parallel to the direction of mean fluid flow within which energy transfer between particles of adjacent heating fluid and cooling fluid streams shall take place by means of contact interchange;

the term 'regenerator' shall refer to a device which transfers thermal energy from hot exhaust gases in a thermal process or cycle to cooler intake fluids normally a part of the same process or cycle;

the term 'atmospheric gas-turbine regenerator' shall relate to a device which partially recovers thermal energy from hot gas turbine exhaust gases that would otherwise be lost on discharge to the atmosphere, by transfer to this thermal energy so as to pre-heat the intake air-fluid stream;

the term 'purge system' shall relate to mechanical means of varying the cross-sectional throat area of an atmospheric exhaust nozzle so as to permit periodically a temporary increase of throat area and so permit an increased discharge from the exhaust nozzle, resulting in a consequent reduction of combustion products concentration within the heating fluid intake stream in fluid system branches downstream of the apparatus of the invention which may be caused by recirculation of entrained combustion products.

While the apparatus of the invention is described in connection with gas turbine exhaust energy recovery for the purpose of improving the power plant thermal efficiency of gas turbine plants exhausting to atmospheric pressures, it will be understood by those skilled in the art that similar structures may be employed in connection with other apparatus where regeneration by means of contact interchange between adjacent fluid streams at different initial pressure is desired.

The primary object of the invention is to provide a means of comparatively simple construction whereby thermal energy present in the exhaust fluid stream of a heat engine, such as a gas turbine, may be partially recovered by means of contact interchange with the cooler, higher-pressure intake fluid stream to the engine.

Another object is the provision of practicable means of contact interchange between the exhaust and intake fluid streams of a gas turbine power plant so as to pre-heat the intake fluid stream before it enters the combustion chamber or other heat source, thereby decreasing fuel consumption and increasing power plant thermal efficiency.

Another object is to provide a practicable means of achieving contact interchange which will accelerate

transfer of thermal energy to conditions approaching thermal equilibrium between the exhaust and intake fluid streams of a gas turbine, or other heat engine, heat source, or thermal process.

Still another object of the invention is to provide a physically feasible means of effecting contact interchange of thermal and kinetic energy between adjacent fluid streams which are at substantially different initial pressures.

A further object is to achieve a regenerator configuration of comparatively simple construction and compact design which will be suitable for use in connection with mobile gas turbine power plants, and for compact, light-weight gas turbine power plants which may be installed as a fixed installation in remote areas.

With the foregoing objects in view, together with others which will appear as the description proceeds, the invention resides in the novel construction, assemblage, and arrangement of parts which will be described more fully in the discussion illustrated in the drawings, and particularly pointed out in the claims.

In the drawings:

FIG. 1 is a fragmentary longitudinal sectional view through an apparatus which involves the teachings of the present invention, the same being shown in the form of a gaseous contact heat exchanger, which is installed as part of the apparatus of a gas turbine power plant exhausting to atmospheric pressures for the purpose of effecting an exchange and transfer of thermal energy between the hot, low-pressure gases exhausted from the turbine and the cooler, higher-pressure fluid stream of incoming air being received from a compressor.

FIG. 2 is an exterior end view of the apparatus illustrated in FIG. 1.

FIG. 3 is a transverse sectional view along line 3—3 of FIG. 1.

FIG. 4 is a transverse sectional view along line 4—4 of FIG. 1.

FIG. 5 is a schematic sectional diagram of a piston-actuated purge control system for periodically lessening combustion products concentration within fluid system branches downstream of the apparatus of the invention, by a mechanical variation of the cross-sectional flow area of an atmospheric exhaust nozzle throat. The purge control apparatus is shown schematically in the extended, or normal operating position.

FIG. 6 is a schematic sectional diagram of the piston-actuated purge control means of FIG. 5 when it is in the retracted, or purge operating position.

FIG. 7 is a schematic process diagram of a gas turbine power plant which incorporates the apparatus of the illustrative embodiment within its flow processes in a conventional manner.

FIG. 8 is a schematic process diagram of a gas turbine power plant which incorporates the apparatus of the illustrative embodiment within its flow processes in an unconventional manner which segregates the combustion process from the power generating process.

FIG. 9 is a schematic sectional diagram of the throat piece operating linkage of FIGS. 5 and 6 when it is actuated by a hand-operated power screw. This control means may be used to adjust exhaust nozzle throat pressure to ambient atmospheric pressure without purging for power systems and processes which do not produce solid products of combustion in their combustion process.

FIG. 10 is a fragmentary longitudinal sectional view through an apparatus having the same application and purpose as the apparatus of FIG. 1. Design is based upon an inversion of the apparatus of FIG. 1.

FIG. 11 is a transverse sectional view taken along line 5—5 of FIG. 10.

FIG. 12 is a transverse sectional view taken along line 6—6 of FIG. 10.

FIG. 13 is an exterior end view of the apparatus illustrated in FIG. 10, taken along line 7—7.

FIG. 14 is a fragmentary longitudinal sectional view through an apparatus which is a multiple variation of the apparatus illustrated in FIG. 10.

FIG. 15 is an exterior end view of the apparatus illustrated in FIG. 14, taken along line 10—10.

FIG. 16 is an exterior upper view of the apparatus illustrated in FIG. 14, including the terminal outlines of the entering and leaving fluid passages.

FIG. 17 is a transverse sectional view taken along line 8—8 of FIG. 14.

FIG. 18 is a transverse sectional view taken along line 9—9 of FIG. 14.

FIG. 19 is an exterior end view of the apparatus illustrated in FIG. 14.

FIG. 20 is a fragmentary longitudinal sectional view of a receiver-side sectional which provides means of axially adjusting the linear position of its central annular intake-fluid nozzle member within the receiver-side section.

FIG. 21 is a substantially exterior longitudinal view of the movable compressed intake-fluid supply pipe and annular nozzle member shown in FIG. 20, together with its actuating linkage.

FIG. 22 is an exterior end view taken along line 11—11 of FIG. 21.

FIG. 23 is a fragmentary longitudinal sectional view of a separator-side section which provides means of axially adjusting the linear position of its central annular pre-heated intake fluid discharge member within the separator-side section.

FIG. 24 is a substantially exterior longitudinal view of the movable annular pre-heated intake-fluid discharge member and discharge pipe as shown in FIG. 23, together with its actuating linkage.

FIG. 25 is an exterior end view taken along line 12—12 of FIG. 24.

FIG. 26 is a fragmentary longitudinal sectional view of a heat exchanger similar to the structure of FIG. 1, which provides a slidable connection in the mid-body of the heat exchanger and means of axially adjusting the linear position of the receiver-side annular nozzle-diffuser member with respect to the separator-side annular exhaust-fluid discharge member.

FIG. 27 is a fragmentary longitudinal sectional view of a heat exchanger similar to the structure of FIG. 10, which provides a slidable connection in the mid-body of the heat exchanger and means of axially adjusting the linear position of the receiver-side intake-fluid nozzle member with respect to the separator-side annular intake-fluid discharge member.

FIG. 28 is an exterior frontal view of a heat exchanger apparatus which may find use in connection with contact heat exchange between the intake air fluid and exhaust gas streams of a steam generator, furnace or other combustion apparatus.

FIG. 29 is a fragmentary longitudinal sectional view along line 11—11 of the heat exchanger apparatus illustrated in FIG. 28.

FIG. 30 is an exterior end view along line 12—12 of the heat exchanger apparatus illustrated in FIG. 28.

FIG. 31 is a transverse sectional view along line 13—13 of the heat exchanger apparatus illustrated in FIG. 29.

FIG. 32 is a transverse sectional view along line 14—14 of the heat exchanger apparatus illustrated in FIG. 29.

FIG. 33 is a modification to the heat exchanger structure of FIG. 28 showing a fragmentary elevation of the receiver-side section wherein pressurized intake fluids supplied by a constant-delivery fan are accelerated within supply ductwork nozzle passageways exterior to the heat exchanger proper, and supplied as high-velocity intake fluids to fluid passageways of the receiver-side section.

FIG. 34 is a fragmentary longitudinal sectional view taken along line 15—15 of FIG. 33.

FIG. 35 is an exterior end view taken along line 16—16 of the heat exchanger apparatus illustrated in FIG. 33.

FIG. 36 is a modification to the heat exchanger structure of FIG. 33 showing a side elevation of intake-fluid supply ductwork for the receiver-side section through which high-velocity intake fluids are supplied to fluid passageways of the receiver-side section from a rotary fan located exterior to the heat exchanger proper.

FIG. 37 is an exterior end view taken along line 17—17 of the intake-fluid supply ductwork illustrated in FIG. 36.

FIG. 38 is a fragmentary sectional modification to the contact heat exchanger structure of FIG. 1 wherein an adjustable coniform flow divider is centrally disposed adjacent the throat section of intake-fluid discharge ductwork to regulate the flow of pre-heated intake fluids through the heat exchanger.

FIG. 39 is a fragmentary sectional modification to the contact heat exchanger structure of FIG. 10 wherein an adjustable coniform flow divider is centrally disposed adjacent the throat section of intake-fluid discharge ductwork to regulate the flow of pre-heated intake fluids through the heat exchanger.

As indicated earlier herein the present invention involves a physical and mechanical arrangement upon the flow processes of a gas turbine power plant, or other similar processes and heat transfer systems, whereby thermal and kinetic energy may be exchanged in parallel flow between adjacent contacting fluid streams traveling at different velocities and having no physical or mechanical separation between them. More exactly, the invention involves an assemblage of ducting chamber sections and opposed sub-sonic, sonic, or super-sonic nozzle-diffuser configurations and combinations which guide the expansion and contraction of fluids at initially different thermodynamic energy states within their several fluid passages to substantially equal pressure states for the purpose of facilitating the transfer of thermal energy between the several fluid streams by contacting interchange, followed by the reseparation of the several fluid streams after the energy transfer process between the has been completed.

The present invention also involves an assemblage of appropriate entrance and exit configurations to the various ducting chamber sections for the purpose of con-

trolling the physical state of the fluid streams which enter and leave the ducting chamber.

According to the teachings of the present invention, low-pressure turbine exhaust gases, acting as the heat source to intake fluids passing through the apparatus 5 enters the receiver-side section of the ducting chamber and are guided to a minimum-velocity, maximum-pressure state by flowing through the interior sub-sonic diffuser passage of a combination nozzle-diffuser member affixed to the exhaust gas entrance pipe or duct within the receiver-side section of the ducting chamber. As shown in the illustrative embodiment of the 10 drawings, the exterior surface of this same nozzle-diffuser member together with the interior walls of the receiver-side section comprise an annular nozzle which 15 may have either a convergent or convergent-divergent configuration. The boundaries of the receiver-side nozzle passage serve to guide the expansion of compressed intakes air fluid to a high-velocity, low-pressure state. 20 As the high-velocity intake heating fluid stream (air) and the low-velocity exhaust cooling fluid stream (combusted turbine exhaust gases) leave their respective sides of the adjacent nozzle and diffuser passages within the receiver-side ducting chamber section at 25 substantially equal pressures, the contact interchange of thermal and kinetic energy between the low-velocity exhaust cooling fluid and the high-velocity intake heating fluid will take place in turbulent flow over a characteristic length within the mixing section of the ducting 30 chamber. After thermal expansion of the intake heating fluid stream and thermal contraction of the exhaust cooling fluid stream has taken place over the characteristic length within the ducting chamber mixing section, the combined adjacent fluid streams are again physically 35 divided on passage into a separator-side section of the ducting chamber. The contracted exhaust cooling fluid now passes into convergent nozzle passage for discharge to the atmosphere. The pre-heated intake heating fluid stream (air) plus a small-scale mixture of entrained combustion products from the exhaust cooling fluid stream, still traveling at a high velocity, enters an annular fluid passage comprised of the interior walls of the separator-side section of the ducting chamber and to the outer walls of the convergent atmospheric exhaust nozzle member. The pre-heated intake fluid stream then leaves the separator-side ducting chamber 40 section and enters a diffuser passage of either the sub-sonic or super-sonic variety, from whence it enters the supply system leading to the combustion chamber. The effect of the apparatus of the invention (often called a regenerator) is to decrease the amount of heat energy which must be supplied by the fuel within the combustion chamber to raise the intake fluid streams to the 45 upper operating temperature, and thus improve the thermal efficiency of the entire gas turbine power plant.

After the high-velocity intake fluid and the low-velocity exhaust fluid streams leave their respective 50 sides of the nozzle-diffuser member and assume intimate contact with each other, highly complex energy transfer relationships between the adjacent fluid streams will exist in their annular interfacial mixing region. Turbulent flow conditions would exist within the high-velocity intake fluid stream as it leaves the exit lip 55 on the nozzle side of the nozzle-diffuser member. Either laminar, transitional or turbulent flow conditions may exist within the low-velocity exhaust fluid stream

as it leaves the exit lip on the diffuser side of the nozzle-diffuser member. A violently turbulent annular mixing region at the interface of the adjacent fluid streams would exist downstream of the nozzle-diffuser member due to the large difference in velocity between the adjacent fluid streams. This turbulent annular mixing region is particularly favorable to the rapid transfer of momentum from the high-velocity intake fluid stream to the low-velocity exhaust fluid stream; and to the accelerated transfer of thermal energy from the higher-temperature exhaust fluid stream to the lower-temperature intake fluid stream.

The annular region of extreme turbulence induced by the violent interchange of momentum between particles of the high-velocity and low-velocity fluid streams is described as the region of contact interchange. At the present time, the complex mechanism of energy transfer between the adjacent fluid streams is only partly understood by those skilled in the art. It has been the general practice in the art to describe flow conditions in a turbulent mixing region in terms of an average velocity plus a fluctuating, time-varying velocity component in the direction of mean flow, together with a fluctuating, time-varying velocity component perpendicular to the direction of mean flow. From this practice has grown theories of turbulent mixing length, concepts of dynamic eddy viscosity for describing momentum interchange in turbulent flow, concepts of eddy diffusivity or eddy heat conductivity for describing the flow of thermal energy across turbulent mixing regions, and other concepts which attempt to scientifically explain mass and energy transport between fluid regions in turbulent flow.

However, it is known from observation, experiment and empirical formulae that highly turbulent mixing zones are extremely favorable for accelerated transfer of thermal energy between adjacent fluid regions.

It should be understood that the fundamental approach to the problem of achieving contact interchange between fluid streams at substantially different thermodynamic energy states and pressures consists of the following stages:

1. Conversion of intake fluid pressure energy to maximum kinetic energy
2. Conversion of exhaust fluid kinetic energy to maximum effective pressure energy
3. Bringing the intake and exhaust fluid streams into physical contact at substantially equal pressures in parallel flow with respect to each other within the confines of a closed plenum or ducting chamber. The object of this stage is to divide flow within the mixing section of the ducting chamber into fluid laminae having greatly different moments.
4. After the energy transfer between the contacting fluid streams is substantially complete, the greatly different momenta of the fluid laminae is utilized to effect a substantial physical separation of the intake and exhaust fluid streams within the separator-side section.
5. The separated fluid streams are then discharged from the separator-side section of the ducting chamber.

Another teaching of the present invention involves an inversion of the design arrangements previously described, which attains similar effects and advantages by means of somewhat different arrangements and related configurations. Low pressure turbine exhaust gases,

acting as heat source to compressed intake fluids (air) passing through the apparatus are guided to a minimum-velocity maximum-pressure state by flowing through an exterior sub-sonic diffuser passage communicating with the receiver-side section of the ducting chamber. The compressed intake fluids are routed into the interior nozzle passage of a central nozzle member by means of a connecting intake fluid supply pipe that pierces the endwall of the receiver-side section, and expanded within the nozzle passage to a high-velocity, low-pressure state. As shown in the drawings, diffused turbine exhaust gases enter the ducting chamber and flow into an annular fluid passage bounded by the exterior walls of the central receiver-side nozzle member and the interior walls of the receiver-side section. The central nozzle passage defined by the interior walls of the receiver-side nozzle member may have either a convergent or convergent-divergent configuration. The adjacent fluid streams leave their respective sides of the receiver-side nozzle member at substantially equal pressures, and flow into the mixing section of the ducting chamber in intimate contact with each other. The contact interchange process takes place as previously described within the mixing section. The large difference in momenta between the intake and exhaust fluid stream is again used to effect separation within the separator-side section of the ducting chamber. The greater inertia of the pre-heated intake fluid stream now carries it substantially past the leading edge of a converging discharge member into a central fluid passage, to which is connected a discharge pipe piercing the confining boundaries of the separator-side section and leading to processes downstream of the invention. The cooled exhaust fluid stream substantially passes into an annular fluid passage bounded by the exterior walls of the separator-side discharge member and the interior walls of the separator-side section, from whence it is exhausted from the apparatus of the invention.

As stated earlier herein, it is among the objects of the present invention to provide a feasible means of achieving contact interchange which will accelerate transfer of thermal energy to conditions approaching thermal equilibrium between the exhaust and intake fluid streams of a gas turbine, or other heat engine, heat source or thermal process. This objective is achieved by an initial large-scale conversion of intake fluid pressure energy to kinetic energy, which in turn aids the establishment of a highly turbulent mixing region between the adjacent fluid streams within the ducting chamber mixing section. It is this violent turbulence, largely induced by the high-velocity intake fluid stream, which will accelerate the large scale transfer of thermal energy from the hot exhaust fluid stream to the relatively cool intake fluid stream. Due to the large velocity difference between the adjacent fluid streams, it is expected that both the mixing and characteristic lengths over which energy transfer is substantially complete will be of modest dimension.

If the contact regenerators described were part of a gas turbine power plant which combusted ordinary refinery fuels, particularly of the heavy residual variety, the concentration of combustion products within the working fluid branch serving the gas turbine would slowly increase. This increase in combustion products concentration within the working fluid branch serving the gas turbine would occur because combustion prod-

ucts entrained in the region of contact interchange would be partially recirculated through the gas turbine rather than being discharged directly to the atmosphere. The rising combustion products concentration in the working fluid stream serving the turbine would result in the build-up of heavy deposits on the blade surfaces of the gas-generator turbine and upon surfaces within the combustion chamber, since solid combustion products would tend to adhere to surfaces in the hotter parts of the thermal process as the solids products melting points are approached. The present invention results in several ways of avoiding this problem, such as:

- I. A purge control method of temporarily increasing atmospheric exhaust nozzle throat area which will evacuate excessive concentration of combustion products from the working fluid branch serving the gas turbine.
- II. A segregation method of arranging gas turbine power plant flow processes which is schematically presented in FIG. 8. This arrangement differs from the more conventional schematic flow process of FIG. 7 in that the regenerator is the sole direct heat source for both the gas-generator turbine and free turbine, and that major quantities of heat energy are added to the exhaust fluid stream by a downstream combustor after expansion of the working fluid has taken place within the turbines. In this method, all but a small percentage of the products of combustion are discharged directly to the atmosphere without passing through the turbines.

It is expected that method I, referred to immediately hereinbefore, or a combination of methods I and II will entirely relieve the solid products deposit problems as it occurs in ordinary practice.

Still another teaching of the present invention involves the arrangement of a plurality of central receiver-side nozzle members within the receiver-side section of an integral plenum or ducting chamber opposing a plurality of converging discharge members within the separator-side section. This multiple version would be useful for effecting contact interchange between the intake and exhaust fluid streams of power plant apparatus involving very large flow rates. As shown in the drawings, the plurality of central receiver-side nozzle members is supplied from a common compressed intake fluid receiver through a plurality of supply pipes which pierce the confining boundaries of the receiver-side section. Hot low-pressure exhaust gases, acting as the heat source to the compressed intake fluids passing through the apparatus, enter the fluid passage defined by the exterior surfaces of the plurality of receiver-side nozzle members and their supply pipes together with the interior walls of the receiver-side section of the ducting chamber. The expansion of the compressed intake fluid streams within the receiver-side nozzle passages to a high-velocity low-pressure state takes place as previously described. The contact interchange process takes place along the plurality of interfacial mixing regions within the mixing section, and the larger inertias of the pre-heated intake fluid streams are again used to separate the intake and exhaust fluid streams within the separator-side section. The pre-heated intake fluid streams are substantially diverted into the plurality of opposed and converging discharge members, which have connecting pipes that pierce the confining boundaries of the separator-side section. The

cooled exhaust fluid stream is substantially diverted into the fluid passage defined by the exterior surfaces of the plurality of converging separator-side discharge members and their supply pipes together with the interior walls of the separator-side section. The pre-heated intake fluid streams are thence routed to processes downstream of the invention, while the cooled exhaust fluid stream is exhausted from the ducting chamber.

Thermodynamic properties of intake fluids (air) entering regenerative atmospheric gas turbine power plants would vary in accordance with ambient atmospheric conditions. This continuing change in the thermodynamic properties of air intake fluids would be reflected as minor variations in the linear dimension of characteristic length over which contact interchange takes place within the regenerative apparatus of the invention. Effective local adjustments between the receiver-side annular nozzle member and the separator-side annular discharge member to the optimum characteristic length becomes necessary to limit formation of normal shock waves in supersonic flow across the leading edge of the annular discharge member of the separator-side section.

Yet another teaching of the present invention involves means of adjusting linear position of the central annular nozzle member within the receiver-side section with respect to the leading edge of its corresponding opposite central annular discharge member of the separator-side section. This arrangement permits local adjustments to the optimum characteristic length dimension within the mixing section of the heat exchanger in accordance with variable atmospheric conditions. The linear position of the central annular discharge member within the separator-side section may be alternately adjusted with respect to the trailing edge of its corresponding opposite central annular nozzle member of the receiver-side section to provide equivalent variable adjustment to optimum characteristic length. The method described for effecting local adjustment to the optimum characteristic length dimension may be applied to either the central annular nozzle members of the receiver-side section or the central annular discharge members of the separator-side section in any of the heat exchangers disclosed in connection with either of FIGS. 1, 10 or 14.

Certain types of gas turbines exhausting to atmospheric pressures which do not produce solid products in their combustion process, such as alcohol-fired turbines, will not require periodic purging of recirculated and entrained combustion products from the working fluid branch serving the gas turbine. Such gas turbine power plants will require a method of adjusting exhaust nozzle throat area so that exhaust nozzle pressure will not exceed atmospheric pressure. The operating linkage of FIGS. 5 and 6 may be actuated by a hand-operated power screw as schematically presented in the sectional diagram of FIG. 9. In this variation, the movable fulcrum pin of the lever together with the operation of the threaded force rod combine to compose an adjustable positioning system which flexibly holds the conical throat piece in a desired position with respect to the atmospheric exhaust nozzle throat so as to effectively control the cross-sectional flow area of the exhaust nozzle.

Heat energy may also be advantageously transferred between the intake air-fluid and exhaust gas streams of a steam generator, furnace or other similar combustion

apparatus by means of the contact-type heat exchanger illustrated in FIGS. 28, 29, 30, 31 and 32. In this apparatus, pressurized intake air is supplied by a forced draft fan and expanded in sub-sonic nozzle passageways of the heat exchanger. The high-velocity intake air-fluid stream and the hot low-velocity exhaust gas stream are each divided into several adjacent alternately contacting fluid streams in parallel flow with respect to each other. Following the contact interchange process, the heated intake fluid streams and the cooled exhaust gas streams are substantially separated from each other. The apparatus shown in FIGS. 28, 29, 30, 31 and 32 would be described in the art as a contact-type air preheater for a steam generator or furnace.

Referring more particularly to the accompanying drawings, FIG. 1 specifically illustrates a longitudinal section of the invention in the form of an atmospheric gas turbine regenerator which is part of the apparatus of an atmospheric gas turbine power plant. In this atmospheric gas turbine regenerator compressed air enters intake fluid supply pipe 8 having a socket flange 9 secured thereto. From this intake fluid supply pipe 8 the compressed air flows into optional sub-sonic diffuser section 11 which is fitted with an entrance flange 10 and an exit flange 12. The compressed intake air-fluid then passes through an entrance flange 13 and into receiver-side ducting chamber section 14. As shown, this receiver side ducting chamber section 14 is provided with an exit flange 15 which is angularly disposed with respect to its entrance flange 13.

The receiver-side ducting chamber section 14 receives hot sub-sonic exhaust gases from the exhaust fluid supply pipe 16 of the turbine or combustor which is centrally disposed therein, extending through the adjacent end wall as shown.

Within the receiver-side ducting chamber section 14, and concentrically disposed with respect thereto is an annular nozzle-diffuser member 17 which is connected to exhaust fluid supply pipe 16 and stabilized by intermediately disposed bracket or spider member 18. The inner surface of the annular nozzle-diffuser member 17 is outwardly flared and defines a diverging sub-sonic diffuser passage 22, wherein the hot exhaust fluid is guided to a thermodynamic energy state of maximum pressure and minimum velocity.

The space between the outer surface of the annular nozzle-diffuser member 17 and the interior of the receiver-side ducting chamber section 14 defines an annular super-sonic nozzle composed of convergent sub-sonic fluid passage 19, annular sonic fluid passage 20, and divergent annular super-sonic fluid passage 21. The purpose of the annular super-sonic nozzle composed of the successive fluid passages 19, 20 and 21 is to guide the expansion of the compressed intake fluid stream until the pressure at the exit lip of the annular super-sonic nozzle is substantially equal to the pressure on the inner side of the nozzle-diffuser member 17, the said exit lip terminating at the end of the sub-sonic diffuser passage 22.

The expanded intake fluid stream leaves the exit lip of the fluid passage 21 traveling at super-sonic speed, while the compressed exhaust fluid stream leaves the exit lip of the diffuser passage 22 traveling at a low sub-sonic speed. As the adjacent high-velocity intake fluid stream and the low-velocity exhaust fluid stream leave the nozzle diffuser member 17 on their respective sides of the exit lip, a violent contact interchange of kinetic

and thermal energy takes place with turbulent mixing along the interface between the adjacent fluid streams.

The exit flange 15 of the receiver-side section 14 is connected to the entrance flange 23 of a cylindrical mixing section 24, the latter being also provided with an exit flange 25.

The aforementioned contact interchange of kinetic and thermal energy between the adjacent fluid streams largely takes place within the boundaries of the mixing section 24. The outer intake heating fluid stream expands within the annular fluid passage region 26 of the mixing section as the thermal energy flows across the annular region of contact interchange, while the inner exhaust cooling fluid stream contracts within the fluid passage region 27 of the mixing section as thermal energy is transferred from the exhaust fluid stream.

The process of contact interchange is substantially complete as the intimately associated fluids leave the outlet of the mixing section 24.

The exit flange 25 of the mixing section 24 is connected to the entrance flange 28 of the separator-side section 29, the latter being also provided with an exit flange 30.

After the intimately associated fluids leave the mixing section 24, they pass into the separator-side section 29 of the ducting chamber and the fluid streams are again divided. Centrally disposed within the separator-side section 29 there is a frusto-conical atmospheric exhaust nozzle member 31, the convergent end of which terminates in a cylindrical throat section 34 which extends through and projects from the adjacent endwall of the separator-side section. Adjacent its larger end the frusto-conical atmospheric exhaust nozzle member 31 is stabilized by bracket or spider members 32.

From the foregoing it will be perceived that the inner exhaust fluid stream enters the converging nozzle passage 33 and exits at atmospheric pressure from the cylindrical throat 34 at the convergent end of the frusto-conical exhaust nozzle member 31. The outer, annular pre-heated intake fluid stream passes into the diverging passage formed by the inner walls of separator-side ducting chamber section 29 and the outer walls of the frusto-conical exhaust nozzle member 31.

Referring to the right-hand side of FIG. 1, a conical divider or throat piece 35 is disposed to extend axially into the exhaust nozzle throat 34, the same being mounted on the end of a slidable control rod 37 and secured by a lock nut 36.

The slidable control rod 37 is mounted to extend through an annular collar 38, the latter being provided with a bushing 39.

This annular collar 38 is supported by a bracket or spider 40 which will be referred to hereinafter.

To the outer end of the separator-side section 29 of the ducting chamber there is secured the annular end flange 41 of the exhaust duct 42, the other end of said exhaust duct being provided with an exterior boss 43 having a bushing 44 extending therethrough.

The bracket or spider 40 which supports the slidable control rod 37 is secured to the interior walls of the exhaust duct 42 and the outer end of said rod extends through and projects from the bushing 44 in the exterior boss 43 on the outer end of the exhaust duct 42.

According to the foregoing construction and arrangement the concial divider or throat piece 35 may be retracted to purge control position 35' which is clear of the throat 34 of the atmospheric exhaust nozzle 31

when the slidable control rod 37 is caused to retract along the longitudinal axis of the ducting chamber by variable force F (see right-hand end of FIG. 1). The temporary increase in cross-sectional flow area occasioned by the retraction of the conical throat piece 35 (to purge control position 35') permits an increased discharge of cooled exhaust gases to the atmosphere through the exhaust duct exit 46 and a consequent purging of the entrained combustion products which may be recirculated within fluid system branches downstream of the apparatus of the invention, as will be understood by those skilled in the art.

As also shown in FIG. 1, the pre-heated intake fluid stream passes through the exit flange 30 of the separator-side section 29 and through the entrance flange 47 of the aforementioned optional diffuser section 48, the latter being also provided with an exit flange 49. While flow conditions may be either sub-sonic or super-sonic at this point depending upon the design parameters chosen for a particular installation, flow velocity is assumed to be supersonic for the purposes of the present illustrative disclosure.

The optional diffuser section 48 is shown as being of inverted frusto-conical shape and its interior walls 50 provide a convergent super-sonic diffuser passage 51 and a lower cylindrical sonic diffuser throat section 52.

Exit flange 49 of the converging super-sonic diffuser member 48 is connected to the entrance socket flange 53 of intake fluid discharge pipe 54.

The pressure drop resulting in moving over the relatively short length of the interior walls 55 of the combustor supply pipe 54 will be sufficient to insure a slightly sub-sonic velocity; accordingly a diverging diffuser section might be added to the combustor supply pipe 54 downstream with respect to the entrance socket flange 53 should a further reduction of the pre-heated intake fluid stream velocity be desired before entering a combustion chamber.

An additional variation for regulating the flow of intake fluids through the contact heat exchanger structure of FIG. 1 is disclosed in the illustrative embodiment of FIG. 38. In FIG. 38 exit flange 49 of optional super-sonic diffuser section 48 (FIG. 1) connects to socket flange 311, the same housing annular sonic throat section 312. Annular sonic throat section 312 is secured by welding or other suitable means to annular sub-sonic diffuser section 313, which is similarly secured to intake-fluid discharge conduit 314. Coniform flow divider or throat piece 317 is suitably attached to the end of slidable control rod 318 and disposed centrally of annular sonic throat section 312 and annular diffuser section 313. Slidable control rod 318 extends through bushing 321 and annular collar 320 of spider assembly 319 (attached to discharge conduit 314), and through bushing 322 and exterior duct boss 315. Variable force F acting on slidable control rod 318 as shown may adjust coniform flow divider or throat piece 317 to any position along the control axis with respect to annular throat section 312 or diffuser section 313. Throat control assembly 317-318 may be actuated by the adjustable pneumatic control apparatus of FIGS. 5 and 6, or by other suitable means.

Intake-fluid discharge throat control assembly 317-318 inclusive and exhaust-fluid throat control assembly 35-37 may be jointly operated by their respective control apparatuses to dampen pressure fluctua-

tions within the contact heat exchanger, or to regulate the contact interchange process.

The schematic diagram of FIG. 7 represents the application of the invention to the thermodynamic processes of an atmospheric gas turbine power plant. Atmospheric air at thermodynamic energy state 56 enters a compressor 57 (driven by the shaft member 66 of the gas-generator turbine 64) where it is compressed to thermodynamic energy state 58. The compressed intake air then enters the regenerative apparatus of the invention (59) where it is pre-heated by contact interchange in parallel flow with the hot exhaust gases of free turbine 67. The pre-heated intake fluid stream leaves the regenerative apparatus of the invention (59) at thermodynamic energy state 60. The pre-heated intake fluid stream then enters combustion chamber 61 where fuel is injected at thermodynamic energy state 62, and combustion then proceeds within the combustor. The high-temperature combusted fluid stream leaves combustion chamber 61 at thermodynamic energy state 63 and is expanded in gas-generator turbine 64 (having a shaft member 66 which drives the compressor 57). The combusted fluid stream leaves the gas-generator turbine 64 at thermodynamic energy state 65, and is further expanded in free turbine 67 having a shaft member 70 which drives an alternator 71 or other work-absorbing device. The combusted fluid leaves the free turbine 67 at thermodynamic energy state 68, and enters the aforementioned regenerative apparatus of the invention (59) in a parallel flow direction with the intake fluid stream traveling between thermodynamic energy states 58 and 60.

Within the regenerative apparatus of the invention (59) the combusted exhaust fluid stream is cooled by contact interchange in parallel flow with the intake fluid stream, and discharged to atmosphere at thermodynamic energy state 69.

The schematic diagram of FIG. 8 represents a novel application of the apparatus of the invention to the thermodynamic processes of an atmospheric gas turbine power plant, wherein the blading of the turbines is substantially protected from fouling by deposit of the products of combustion. All of the initial heating of intake air-fluid is accomplished within the regenerative apparatus of the invention (59) and the combustion process is entirely carried out in the free turbine exhaust fluid stream. Save for a small amount of entrained combustion products within the pre-heated intake fluid stream, no combustion products will pass directly through the gas-generator turbine 64 or the free turbine 67. The fouling of blading surfaces within the turbines by deposit of the products of combustion is thus bypassed almost entirely by the method of segregation.

Referring still to FIG. 8, atmospheric air at thermodynamic energy state 56 enters compressor 57 (driven by the shaft member 66 of the gas-generator turbine 64) where it is compressed to thermodynamic energy state 95. The compressed intake air stream then enters the regenerative apparatus of the invention (59) where it is pre-heated by contact interchange in parallel flow with the high-temperature exhaust gases from combustion chamber 61. The pre-heated intake fluid stream leaves the regenerative apparatus of the invention (59) at thermodynamic energy state 96, and is then expanded in gas-generator turbine 64 (driving compressor 57, etc.). The pre-heated fluid stream leaves gas-

generator turbine 64 at thermodynamic energy state 97, and is then further expanded in free turbine 67 (having shaft member 70 which drives alternator 71 or other work-absorbing device). The expanded fluid stream leaves free turbine 67 at thermodynamic energy state 98, and enters the combustion chamber 61. Within the combustion chamber 61 fuel is injected at thermodynamic energy state 99, and the combustion process proceeds therewithin. The combusted high-temperature exhaust fluid stream leaves the combustion chamber 61 at thermodynamic energy state 100, and enters the regenerative apparatus of the invention (59) in parallel flow with the intake fluid stream traveling between thermodynamic energy states 95 and 96. Within the regenerative apparatus of the invention (59) the combusted exhaust fluid stream is cooled by contact interchange in parallel flow with the intake fluid stream, and then discharged to atmosphere at thermodynamic energy state 101.

FIG. 5 is a schematic diagram partially in section, of a piston-actuated control system for carrying out the purging operation on a cyclical basis. In this figure the pneumatic control system is illustrated when it is approaching the normal operating position, wherein the conical flow divider or throat piece 35 would be nearly disposed in the correct position with respect to exhaust nozzle throat 34 of the atmospheric exhaust nozzle member 31. As shown, the slideable control rod 37 carries a yoke fitting 72 which houses a yoke pin 73. A lever 74 is provided with a guide slot 75 for receiving the yoke pin 73; and in this manner the motion of the lever 74 is transmitted to the slideable control rod 37.

The lever 74 pivots about an adjustable fulcrum pin 76 and has a guide slot 77 within which a yoke pin 78 is slidably disposed. This yoke 78 is housed in a yoke fitting 79 and the adjustable fulcrum pin 76 is housed by a traveler member 80 which is threaded onto a power screw member 81. This power screw member 81 is housed in machine-frame socket member 82 by a suitable sleeve-type bushing, and in machine-frame bearing member 83 by sleeve-type bushing and thrust collars. A handwheel 84 rotates this power screw member 81 to cause the traveler member 80 to advance or retract along the threaded shaft, thus adjusting the linear position of the fulcrum pin 76.

The yoke fitting 79 is secured to the piston rod 85 of a pneumatic double-acting piston 86 which is disposed in a cylinder 87, and in this manner the movement of said piston is transmitted to the slideable control rod 37.

The numerals 88 and 89 designate pipe branch members which are connected to the upper and lower left-hand orifices of a four-way valve 90.

A pneumatic supply pipe 91 is connected to the upper right-hand orifice of the four-way valve 90, and an exhaust pipe 92 is connected to the lower right-hand orifice thereof.

A solenoid 93, forming part of an electrical pilot circuit 94, may be utilized to control the operation of the double-acting piston 86 in the cylinder 87. When the solenoid 93 is de-energized, compressed air will flow from the pneumatic supply pipe 91 into the upper right-hand orifice of the four-way valve 90 into the pipe branch member 88 with the direction of flow indicated by the arrows. In this manner the compressed air enters the cylinder 87 to act upon the rod face of piston 86, causing the piston to move to the right as viewed in the drawings. This movement of the piston 86 exhausts

low-pressure air from the cylinder 87 into the pipe branch member 89, which communicates with the lower left-hand orifice of the four-way valve 90. Exhausted air then flows through the four-way valve 90 into the exhaust pipe 92 (which communicates with the lower right-hand orifice of the four-way valve), from whence the exhaust air leaves the pneumatic control system.

It will be understood that the installation of an additional cross-over valve connection between the pneumatic supply pipe 91 and the exhaust pipe system 92 downstream of the aforementioned four-way valve plus a stop valve fitting within the exhaust pipe 92 system downstream of said crossover valve connection will permit the pneumatic control system to hold the piston 86 in any desired operating position within the cylinder 87.

FIG. 6 is a schematic diagram, partly in section, of the pneumatic purge control system, wherein the apparatus of the control system is shown as nearing the retracted purge operating position. The movement of the piston 86 within the cylinder 87 is now disclosed as opposite to that illustrated in FIG. 5; and the control system linkage has retracted the conical throat piece 35 from the exhaust nozzle throat 34.

According to FIG. 6, the solenoid 93 has been energized by the electrical pilot circuit 94, thereby actuating the four-way valve 90 to cross-route the compressed air supply from the pneumatic supply pipe 91 to the pipe branch member 89. Thus, the compressed air enters the cylinder 87 to act upon the head face of the piston 86, causing the piston to move within the cylinder 87 to the left as illustrated. This movement of the piston 86 exhausts low-pressure air from the cylinder 87 into the pipe branch member 88. The exhausted low-pressure air is then cross-routed from the pipe branch member 88 to the pneumatic exhaust pipe 92 by the four-way valve 90, from whence the exhaust air leaves the pneumatic control system.

In this connection, it will be understood that the installation of an additional crossover valve connection between the pneumatic supply pipe 91 and the pneumatic exhaust pipe 92, together with a stop valve fitting within the exhaust pipe system 92 downstream of the additional crossover valve connection will permit the pneumatic control system to hold the piston 86 in any desired operating position within the cylinder 87, when said stop and crossover valves are jointly operated.

FIG. 9 is a schematic diagram of the throat piece operating linkage of FIGS. 5 and 6 (i.e. adjustable lever type) as actuated by a hand operated power screw. This form of throatpiece control apparatus may be utilized to insure that exhaust nozzle discharge and throat pressures are adjusted to the optimum conditions consistent with ambient atmospheric conditions, simply by adjusting the position of the conical throat piece 35 with respect to the exhaust nozzle throat 34. According to this embodiment there is no provision for a cyclic retraction of the conical throat piece 35 from the exhaust nozzle throat 34 as occurs in the purge control apparatus illustrated in FIGS. 5 and 6, since the hand-operated type is for use in connection with the regenerative apparatus of gas turbine power plants exhausting to atmospheric pressures and which do not produce solid combustion products in their combustion process.

Rotation of the handwheel 105 imparts similar movement to the power screw shaft member 103 within the

threaded machine-frame housing 104, causing the power screw shaft member to advance or retract with respect to the said machine-frame housing. The end of the power screw shaft member 103 opposite to that carrying the handwheel 105 is fitted with a tuned and necked end which may rotate freely within the socket member 102 which is affixed to the yoke fitting 79. The power screw shaft member 103 may be additionally stabilized by a sleeve-type bushing housed in an additional machine-frame bearing member, or by other suitable means. The lever-type linkage of FIG. 9 functions similarly to the lever-type linkage of FIGS. 5 and 6 when the double-acting piston 86 is held in a fixed position, wherein the position of the conical throat piece 35 is adjustable by both the actuating power screw shaft member 103 and the fulcrum screw shaft member 81 acting separately or in conjunction with each other.

FIG. 10 specifically illustrates a longitudinal section of the invention in the form of an atmospheric gas turbine regenerator whose design represents an inversion of the illustrative embodiment of FIG. 1. Hot low-pressure turbine exhaust gases enter exhaust fluid supply pipe 106, which is fitted with exit flange 107. Exit flange 107 of exhaust fluid supply pipe 106 is connected to entrance flange 108 of diffuser member 109, the latter also being provided with exit flange 110. The hot-low pressure exhaust gases flow from supply pipe 106 into an interior diffuser passage of diffuser member 109 defined by interior walls 111, where they are guided to a minimum-velocity, maximum pressure state. Exit flange 110 of diffuser member 109 is connected to entrance flange 112 of receiver-side section 113, the latter also being provided with angularly disposed exit flange 114. The compressed exhaust gases pass from diffuser member 109 into receiver-side section 113 through its entrance flange 112.

Receiver-side ducting chamber section 113 receives compressed intake fluid (air) from intake fluid supply pipe 115, which is centrally disposed and extends through the adjacent endwall as shown.

Within receiver-side ducting chamber section 113 and concentrically disposed with respect thereto is an annular nozzle member 116, which is connected to intake fluid supply pipe 115 and stabilized by intermediate disposed bracket or spider members 117. The inner surface of receiver-side nozzle member 116 defines the boundaries of a convergent-divergent nozzle composed of sub-sonic nozzle passage 118, sonic nozzle passage 119 and super-sonic nozzle passage 120. Within the receiver-side nozzle passage 118, 119 and 120, the compressed intake fluid stream is guided and expanded to a high-velocity, low-pressure state. The space between the outer surface of annular nozzle member 116 and the interior walls of receiver-side section 113 composes an annular fluid passage 121, which is in turn supplied with compressed exhaust gases from diffuser member 109. The purpose of the super-sonic nozzle composed of successive fluid passages 118, 119 and 120 is to guide the expansion of the compressed intake fluid stream until the pressure at the exit lip of the super-sonic nozzle is substantially equal to the pressure of the hot exhaust gases on the outer side of annular nozzle member 116 in exhaust fluid passage 121.

The expanded intake fluid stream leaves the exit lip of fluid passage 120 traveling at super-sonic speed, while the compressed exhaust fluid stream leaves annular exhaust fluid passage 121 traveling at a low sub-

sonic speed. As the adjacent high-velocity intake fluid stream and the low-velocity exhaust fluid stream leave annular nozzle member 116 on their respective sides of the exit lip, a violent contact interchange of kinetic and thermal energy takes place with turbulent mixing along the annular interface between the adjacent fluid streams.

The adjacent intake and exhaust fluid streams leave receiver-side section 113 and pass into mixing section 123, which is fitted with entrance flange 122 and exit flange 124. Exit flange 114 of receiver-side section 113 is connected to entrance flange 122 of mixing section 123.

The previously mentioned contact interchange of thermal and kinetic energy between the adjacent fluid streams largely takes place within the boundaries of mixing section 123. The inner high-velocity intake heating fluid stream expands within the inner fluid passage region 126 of the mixing section as thermal energy flows across the annular interfacial region of contact interchange, while the outer exhaust cooling fluid stream contracts within annular fluid passage region 125 of the mixing section as thermal energy is transferred from the exhaust fluid stream. The process of contact interchange is substantially complete as the intimately associated fluid streams leave the outlet of mixing section 123.

Exit flange 124 of mixing section 123 is connected to entrance flange 127 of separator-side section 128, the latter being provided with angularly disposed exit flange 129.

After the intimately associated fluid stream leave the mixing section 123, they pass into separator-side section 128 of the ducting chamber and the fluid streams are again divided. Centrally disposed within separator-side section 128 there is a frusto-conical discharge member 130, the convergent end of which is connected to discharge pipe member 131, which in turn pierces the endwall of separator-side section 128. The substantially greater inertia of the pre-heated intake fluid stream carries it past the entrance lip of separator-side discharge member 130 into convergent fluid passage 132 defined by the interior walls of the aforesaid discharge member. Adjacent its larger end, the convergent discharge member 130 is stabilized by intermediate disposed bracket or spider members 133. The pre-heated intake fluid stream is discharged from discharge fluid passage 132 through discharge pipe 131 from the ducting chamber to processes downstream of the invention.

After passing the entrance lip of separator-side discharge member 130, the cooled exhaust fluid stream enters the converging annular exhaust fluid passage 134, defined by the exterior surfaces of the convergent discharge member 130 and its connecting discharge pipe 131 together with the converging interior walls of the separator-side section. It should be particularly noted that the walls of separator-side section 128 converge from the inlet at the entrance flange 127 to the outlet at the angularly disposed exit flange 129.

Exit flange 129 of separator-side section 128 is connected to entrance flange 142 of atmospheric exhaust duct 144, from which the cooled exhaust fluid is finally exhausted to the atmosphere.

The reduction in cross sectional exhaust fluid flow area within the separator-side section composes an effective convergent exhaust nozzle which terminates in

exhaust bore or throat 135 formed by the inner surfaces of exit flange 129 of the separator-side section and the entrance flange 142 of atmospheric exhaust duct 144. A conical divider or throat piece 136 is disposed to extend axially into exhaust nozzle throat 135. The conical throat piece 136 is centrally mounted and positioned along the axis of exhaust nozzle throat 135 at the end of slidable control rod 138, and secured thereto by a lock nut 137.

The slidable control rod 138 is mounted to extend through annular collar 139, the latter being provided with a bushing 140. Slidable control rod 138 also extends through exterior boss 145 of atmospheric exhaust duct 144, the exterior boss being provided with a bushing 146 extending therethrough. Annular collar 139 is stabilized along the longitudinal axis of the atmospheric exhaust duct 144 by bracket or spider members 141.

It should be noted that divergent flare section 143 of atmospheric exhaust duct 144 is provided to reduce pressure drop and to improve exhaust fluid flow conditions in the vicinity of exhaust nozzle throat 135 with respect to conical divider or throat piece 136.

It is apparent from the foregoing construction that the conical throat piece 136 may be positioned along the axis of exhaust nozzle throat 135 by variable force F acting upon the slidable control rod 138 exterior to exhaust duct shaft boss 145. Conical divider or throat piece 136 may be retracted to purge control position 136', which is clear of throat section 135 of the atmospheric exhaust nozzle formed by the interior walls of separator-side section 128. The retraction of conical throat piece 136 to purge control position 136' permits an increased discharge of cooled exhaust gases from the exhaust nozzle throat, and a consequent purging of entrained combustion products which may be recirculated through fluid system branches downstream of the apparatus of the invention, as will be understood by those skilled in the art.

An additional variation for regulating the flow of intake fluids through the contact heat exchanger structure of FIG. 10 is disclosed in the illustrative embodiment of FIG. 39. In FIG. 39 intake-fluid discharge duct 131 (FIG. 10) is connected by welding or other suitable means to uniform annular sonic throat section 323, which is similarly secured to annular sub-sonic diffuser section 324. Annular sub-sonic diffuser section 324 is secured by welding or other suitable means to intake-fluid discharge conduit 325. Coniform flow divider or throat piece 328 is suitably attached to the end of slid- 40 able control rod 329 and disposed centrally of annular sonic throat section 323 and annular diffuser section 324. Slidable control rod 329 extends through bushing 332 and annular collar 331 of spider assembly 330 (attached to discharge conduit 325), and also extends through bushing 333 and exterior duct boss 326. Variable force F acting on slidable control rod 329 as shown may adjust coniform flow divider or throat piece 328 to any position along the control axis with respect to annular throat section 323 or diffuser section 324. Throat control assembly 328-329 may be actuated by the adjustable pneumatic control apparatus of FIGS. 5 and 6, or by other suitable means.

Intake-fluid discharge throat control assembly 328-329 inclusive and exhaust-fluid throat control assembly 136-138 inclusive may be jointly operated by their respective control apparatuses to dampen pres-

sure fluctuations within the contact heat exchanger, or to regulate the contact interchange process.

FIG. 14 specifically illustrates a longitudinal section of the invention in the form of a multiple variation of the apparatus of FIG. 10. The apparatus of FIG. 14 may find utility as part of the heat exchange equipment of power plant systems involving large flow rates of the working fluid.

Compressed intake fluids pass through entrance flange 149 of distribution receiver 150-151, composed of shell piece 150 and back piece 151. Intake fluid distribution receiver 150-151 may be fabricated by cast-weld or other suitable assembly techniques. A plurality of intake fluid nozzle supply pipes 153 pierce back piece 151 of distribution receiver 150-151, and are secured thereto by rolling at the entrance ends 152 of the intake fluid nozzle supply pipes. Back piece 151 of intake fluid distribution receiver 150-151 and circumferential flange 155 of integral ducting chamber 156 are joined together by welding or other suitable connecting means.

From distribution receiver 150-151, compressed intake fluids flow into the plurality of nozzle supply pipes 153, which are in turn connected to a plurality of convergent-divergent nozzle members 154 intermediately disposed within receiver-side section 156' of integral ducting chamber 156. The compressed intake fluid is expanded successively in sub-sonic nozzle passage 165, sonic nozzle passage 166 and super-sonic nozzle passage 167 of individual nozzle members 154 to a high-velocity, low-pressure state. Intermediately disposed nozzle members 154 are stabilized within receiver-side section 156' by a framework of bracket members 164 secured to adjacent nozzle members 154 or the inner walls of receiver-side section 156' of integral ducting chamber 156.

Hot low-pressure exhaust gases enter the necked exhaust fluid entrance duct 157 extending from the confining side walls of receiver-side section 156'. The hot exhaust gases flow into the receiver-side section 156' and are diffused within the fluid passage 168 between the outer surfaces of intake fluid nozzle members 154 and their connecting supply pipes 153 together with the interior walls of the receiver-side section 156'. It should be noted that flow pieces 162 and 163 at the upper and lower left-hand corners within the receiver-side section 156' are secured between the interior walls of the receiver-side section and back piece 151 of intake fluid distribution receiver 150-151. The purpose of flow pieces 162 and 163 is to reduce pressure drops in the exhaust fluid stream in the vicinity of corners within the receiver-side section.

The previously discussed contact interchange of thermal and kinetic energy between the adjacent fluid streams largely takes place within mixing section 159 (shown in phantom) of integral ducting chamber 156 after the intake and exhaust fluid streams leave their respective sides of the exit lips of receiver-side nozzle members 154. The inner high-velocity intake heating fluid streams expand within integral fluid passage regions 170 as thermal energy flows across the annular interfacial regions of contact interchange. The outer exhaust cooling fluid stream contracts within surrounding fluid passage regions 169 as thermal energy is transferred from the exhaust fluid stream. The contact interchange process is substantially complete as the inti-

mately associated fluid stream leave mixing section 159 (shown in phantom).

A plurality of converging annular discharge members 173 are intermediately disposed within separator-side section 156" of integral ducting chamber 156, and stabilized therewithin by a framework of bracket members 174 secured to adjacent discharge members 173 or the inner walls of the separator-side section. Converging annular discharge members 173 are individually connected to discharge pipes 175, which in turn pierce the confining endwall of the separator-side section 156".

The greater inertias of the pre-heated intake fluid streams carries them out of mixing section 159 and substantially into the converging fluid passages 172 of annular discharge members 173. The pre-heated intake fluid streams are discharged from converging fluid passages 172 to processes downstream of the apparatus of the invention by means of discharge pipes 175.

The cooled exhaust fluid stream leaves mixing section 159 and passes the outer sides of the entrance lip of annular discharge members 173. The cooled exhaust fluid stream enters converging fluid passage 171, which is defined by the exterior surfaces of annular discharge members 173 and their connecting discharge pipes 175 together with the interior walls of the separator-side section 156". Cooled exhaust gases next enter the necked exhaust duct 160, which extends from the confining sidewalls of separator-side section 156". The cooled exhaust fluid leaves the apparatus of the invention through exit flange 161 of necked exhaust duct 160.

It should be noted that the confining boundaries of the integral ducting chamber 156 converge from approximately the region of necked exhaust fluid entrance duct 157 to the region of necked exhaust duct 160. It is seen from the foregoing construction that an effective converging nozzle is defined by the confining walls of the integral ducting chamber 156, and that the terminal throat section is defined by the cross section of necked exhaust duct 160.

It should also be noted that purge control apparatus including a coniform divider or throat piece mounted upon the end of a slidable control rod may be utilized and mounted exterior to exhaust duct flange 161, to regulate the flow of cooled exhaust fluid exhausted from the integral ducting chamber.

FIGS. 20-25 specifically illustrate several variations of the illustrative embodiment of FIG. 10, which provide for the linear adjustment to optimum characteristic length in accordance with changes in thermodynamic properties of atmospheric air intake fluids. The type of linear adjustment disclosed is necessary to limit the possible formation of normal shock waves in supersonic flow within the intake fluid stream across the leading edge of the annular discharge member of the separator-side section.

The method of linear adjustment disclosed in FIGS. 20-22 is independent of and separate from the method disclosed in FIGS. 23-25. The adjustable receiver-side intake fluid nozzle assembly of FIGS. 20-22 would normally discharge to an oppositely-disposed fixed annular discharge member of the separator-side section. The adjustable separator-side intake fluid discharge assembly of FIGS. 23-25 would normally receive high-velocity intake fluids from an oppositely-disposed fixed intake fluid nozzle assembly of the receiver-side section.

Receiver-side section 177 of FIG. 20 is somewhat similar in function to receiver-side section 113 of FIG. 10. Hot low-pressure exhaust gases enter receiver-side section 177 through entrance flange 176, the latter entrance flange 176 being angularly disposed with respect to exit flange 178. Receiver-side section 177 is provided with boss section 179, which is configured to slidably house compressed intake-fluid supply pipe 180.

Compressed intake-fluid supply pipe 180 is connected to central annular nozzle member 181, whose inner surfaces define the boundaries of a convergent-divergent nozzle composed of subsonic fluid passage 184, sonic fluid passage 185 and supersonic fluid passage 186. Central annular nozzle member 181 is stabilized within receiver-side section 177 by slidable spider assembly 182-183. Spider assembly 182-183 is composed of intermediately disposed bracket or spider members 182 and bearing ring 183. Bearing ring 183 slides along the interior surface of receiver-side section

177. Compressed intake-fluid supply pipe 180 and attached annular nozzle member 181 together with spider assembly 182-183 all slide together along the longitudinal axis of receiver-side section 177 as shown in FIGS. 20, 21 and 22.

Exterior linkage 188-195 will transmit sliding motion to intake fluid nozzle assembly 180-183 within receiver-side section 177 in alternate directions when acted on by variable force F.

Variable force F acts on rod member 188 having attached yoke fitting 189 housing yoke pin 191 within guide slot 190. Yoke pin 191 is attached to yoke lever 192, which pivots about fulcrum pin 194. Fulcrum pin 194 is housed in heel fitting 193. The base of heel fitting 193 is secured at the base thereof by any suitable means to the exterior of receiver-side section 177.

Yoke lever 192 provides guide slots 195 individually in each of its upper arms. Each of the guide slots 195 house axially opposite yoke pins 196. Separate yoke pins 196 are secured opposite each other on the exterior surface of compressed intake fluid supply pipe 180.

The function of separator-side section 198 in FIG. 23 is somewhat similar to that of separator-side section 128 in FIG. 10. Cooled low-pressure exhaust gases enter annular exhaust-fluid passage 201 of separator-side section 198 through entrance flange 197. Entrance flange 197 of separator-side section 198 is angularly disposed with respect to exit flange 199. Separator-side section 198 is provided with boss section 200, which is configured to slidably house intake-fluid discharge pipe 204.

Central annular discharge member 203 is connected to pre-heated intake-fluid discharge pipe 204. The inner surface of central annular discharge member 203 defines the boundary of convergent fluid passage 205. Spider assembly 206-207 is composed of intermediately disposed bracket or spider members 206 and bearing ring 207. Bearing ring 207 slides along the interior surface of separator-side section 198. Pre-heated intake-fluid discharge pipe 204 and attached central annular discharge member 203 together with spider assembly 206-207 all slide together along the longitudinal axis of separator-side section 198 as shown in FIGS. 23, 24 and 25.

Exterior linkage 188-195 as previously described transmits sliding motion to intake fluid discharge assembly 203-207 within separator-side section 198 in alternate direction when acted on by variable force F.

The motion of exterior linkage 188-195 is transmitted to intake fluid discharge assembly 203-207 by way of separate yoke pins 208. Separate yoke pins 208 are secured opposite each other on the exterior surface of pre-heated intake fluid discharge pipe 204.

It is obvious that the arrangement within receiver-side section 14 of FIG. 1 may be similarly modified so that exhaust fluid nozzle-diffuser assembly 16-17 is slidably disposed along the longitudinal axis in the manner previously described. It is also evident that the arrangement within the separator-side section 29 may also be modified so that central annular exhaust-fluid discharge member 31-34 is slidably disposed along the longitudinal axis of the separator-side section.

Arrangements within receiver-side section 156' of integral ducting chamber 156 in FIG. 14 may also be modified so that the plurality of intake-fluid nozzle assembly members 153-154 are slidably disposed along parallel longitudinal axes opposite their respective fixed companion intake fluid discharge members 173 and 175. Separator-side section 156'' of integral ducting chamber 156 in FIG. 14 may also be easily modified so that the plurality of intake-fluid discharge assembly members 173 and 175 are slidably disposed along parallel longitudinal axes opposite their respective fixed companion intake-fluid nozzle assembly members 153-154.

FIGS. 26 and 27 illustrate alternate means of variably adjusting characteristic length of the contact interchange process, to limit formation of normal shock in accordance with the variation of ambient atmospheric pressure and temperature. The heat exchanger structure of FIG. 26 is provided with a slidable connection in the duct between the receiver-side and separator-side sections, but is otherwise functionally similar to the structure of FIG. 1. The heat exchanger structure of FIG. 27 is provided with a slidable connection in the duct between the receiver-side and separator-side sections, but is otherwise functionally similar to the structure of FIG. 10.

Referring to FIG. 26, hot low-pressure exhaust fluids enter supply pipe 212, to which annular nozzle-diffuser member 213 is attached. Annular nozzle-diffuser member 213 is stabilized within receiver-side section 210 by intermediately disposed bracket or spider members 214, and its interior surface defines the boundary of diffuser passage 218. Compressed intake fluids enter receiver-side section 210 through the opening of entrance flange 209, and are expanded in the super-sonic nozzle composed of successive sub-sonic nozzle passage 215, sonic fluid passage 216 and super-sonic nozzle passage 217. The cool high-velocity intake-fluid and hot low-velocity exhaust-fluid streams leave their respective sides of annular nozzle-diffuser member 213 at substantially equal pressures, and flow into the mixing zone composed of outer annular fluid passage region 220 and internal fluid passage region 219. The contact interchange process takes place between the high-velocity intake-fluid and the low-velocity exhaust-fluid streams within the mixing zone as previously described.

Cooled exhaust fluids from internal fluid passage region 219 of the mixing zone enter the converging exhaust-fluid discharge passage 226 of exhaust-fluid discharge member 224, and are discharged to atmosphere through nozzle throat 227. Exhaust-fluid discharge member 224 is stabilized within separator-side section 222 by intermediately disposed bracket or spider mem-

bers 225. Heated high-velocity intake fluids from outer annular fluid passage region 220 of the mixing zone enter the outer annular fluid passage of the separator-side section, and are discharged to apparatus downstream of the heat exchanger through the opening of exit flange 223.

Rounded duct end 211 of receiver-side section 210 envelopes beveled duct end 221 of separator-side section 222 to form a slidable joint in the mid-body of the heat exchanger shown in FIG. 26. The elongate separator-side section 222 would normally be held fixed by rigid machine frame members. Slidable receiver-side section 210 may have its linear position adjusted along the flow axis of the heat exchanger by the section of variable force F, as shown at the lower left-hand side of FIG. 26.

Axial guide member 228 having a suitable linear guide bar is secured to the lower part of receiver-side section 210 by any suitable means as shown. The linear guide bar of axial guide member 228 is slidably disposed in axial guide bar housing 229. Axial guide bar housing 229 is rigidly secured to any convenient machine frame member 230. Operating rod 231 is rigidly attached to axial guide member 228. Variable force F acting on operating rod 231 may slidably adjust the entire receiver-side assembly 209-218 along the flow axis of the heat exchanger, thereby altering the characteristic length of the contact interchange process in the mixing zone.

Referring to FIG. 27, compressed intake fluids enter supply pipe 235 to which is attached annular super-sonic nozzle member 236. Annular super-sonic nozzle member 236 is stabilized within receiver-side section 233 by intermediately disposed bracket or spider members 237. Hot low-pressure exhaust fluids enter receiver-side section 233 through the opening of entrance flange 232 and flow into annular exhaust-fluid passage 241. Compressed intake fluids are expanded in super-sonic nozzle 236, the same providing successive sub-sonic nozzle passage 238, sonic fluid passage 239 and super-sonic nozzle passage 240. The cool high-velocity intake-fluid and hot low-velocity exhaust-fluid streams leave their respective sides of nozzle member 236 at substantially equal pressures, and flow into the mixing zone composed of internal fluid passage region 243 and outer annular fluid passage region 242. The contact interchange process takes place between the high-velocity intake-fluid and the low-velocity exhaust-fluid streams within the mixing zone as previously described.

Heated intake fluids from internal fluid passage region 243 of the mixing zone enter the converging internal fluid passage 249 of annular discharge member 247, the same being connected to intake-fluid discharge pipe 248. Annular intake-fluid discharge member 247 is stabilized within separator-side section 245 by intermediately disposed bracket or spider members 250. Cooled exhaust fluids from outer annular fluid passage region 242 of the mixing zone enter the outer annular fluid passage 251 of separator-side section 245, and are discharged through the opening of exit flange 246 to atmosphere.

Rounded duct end 234 of receiver-side section 233 envelopes beveled duct end 244 of separator-side section 245 to form a slidable joint in the mid-body of the heat exchanger shown in FIG. 27. Receiver-side section 233 would normally be held fixed by rigid machine frame members. Slidable separator-side section 245

may have its linear position adjusted along the flow axis of the heat exchanger by the action of variable force F, as shown at the lower right-hand side of FIG. 27.

Axial guide member 252 having a suitable linear guide bar is secured to the lower part of separator-side section 245 by any suitable means as shown. The linear guide bar of axial guide member 252 is slidably disposed in axial guide bar housing 253. Axial guide bar housing 253 is rigidly secured to any convenient machine frame member 254. Operating rod 255 is rigidly attached to axial guide member 252. Variable force F acting on operating rod 255 may slidably adjust the entire separator-side assembly 245-251 along the flow axis of the heat exchanger, thereby altering the characteristic length of the contact interchange process in the mixing zone.

The mid-body of the integral duct forming the heat exchanger structure disclosed in connection with FIG. 14 and described earlier may be similarly altered to vary characteristic length of the contact interchange process in multiple-nozzle heat exchangers. A slideable joint is formed in the common duct between the receiver-side and separator-side sections, and the slideable separator-side assembly would be axially adjusted by a variable exterior force acting on an axial guide. Since this heat exchanger is but a plural form of the structure disclosed in FIG. 10, no further description of this variation will be made.

Other low-velocity variations of this contact heat exchanger invention may find use as pre-heaters for intake air fluids entering a furnace, steam generator, etc. In these forms of the invention, the intake air-fluid stream would enter the mixing section at a relatively low sub-sonic velocity while the exhaust fluid stream entered the mixing section at a velocity considerably less than that of the intake fluid stream. Auxiliary flow control apparatus such as discussed hereinbefore would have optional use, and such apparatus would become more desirable as intake stream velocity within the mixing section approached sonic values.

Referring to FIGS. 28, 29, 30, 31 and 32 hot low-velocity exhaust gases enter receiver-side section 257' through peripheral flange 256 of integral ducting chamber 257. Integral ducting chamber 257 provides receiver-side section 257' and downstream separator-side section 257'', with mixing section 271 (shown in phantom) disposed therebetween. The cooled exhaust gases are discharged from separator-side section 257'' through peripheral exit flange 258 after the contact interchange process.

Within receiver-side section 257', the hot exhaust gases are divided into several narrow streams by flow dividers 267. Flow dividers 267 extend between the top and bottom walls of receiver-side section 257'. Flow dividers 267 abut end plates 265 adjacent partition members 263 and 264. As viewed along line 13-13, similar right-hand partition members 263 and similar left-hand partition members 264 are seen to extend between the top and bottom walls of receiver-side section 257', and to partly define the plurality of exhaust fluid passageways 268.

Pressurized intake air fluids are supplied to the receiver-side section 257' by a forced-draft fan or other suitable fluid pump. Pressurized intake air fluids enter similar supply ducts 260 and 262 through their respective entrance flanges 259 and 261. Intake fluid supply ducts 260 and 262 each deliver their respective intake

air fluid stream into a similar fluid passageway which terminates in nozzle passage 266. The internal intake fluid passages of receiver-side section 257' are each defined by end plate 265, right-hand partition member 263, and left-hand partition member 264, together with the top and bottom walls of the receiver-side section. Partition members 263 and 264 are each configured to collectively provide the accelerating nozzle passage 266 at the discharge end thereof.

- 10 Elongate fluid jets in the vertical plane along longitudinal axes of the heat exchanger are discharged into mixing section 271 (shown in phantom) from the plurality of nozzle passages 266 within receiver-side section 257'. Within the mixing section, the high-velocity intake heating fluid streams occupy fluid passage regions 270 while the low-velocity exhaust cooling fluid streams occupy fluid passage regions 269 respectively. The contact interchange of thermal and kinetic energy between the intake fluid and exhaust fluid streams 15 takes place as previously described. The contact interchange process is substantially complete as the heated intake fluid streams and the cooled exhaust fluid streams are discharged from mixing section 271 into separator-side section 257''.
- 20 25 The heated high-velocity intake fluid streams each enter a similar converging fluid discharge passage 272 of separator-side section 257''. As viewed along line 14-14, similar left-hand partition members 273 and similar right-hand partition members 274 are seen to 30 extend between the top and bottom walls of separator-side section 257'', and to partly define the plurality of converging intake fluid discharge passageways 272. Partition members 273 and 274 are each configured to 35 collectively provide the converging fluid discharge passage 272 at the entrance end thereof. Each intake fluid discharge passage of separator-side section 257'' is defined by left-hand partition member 273, right-hand partition member 274, and end plate 275, together with the top and bottom walls of the separator-side section.
- 40 45 The heated intake fluid streams leave their respective fluid passageways 272 of the separator-side section to enter similar discharge ducts 278 and 280. Similar intake fluid discharge ducts 278 and 280 are provided with exit flanges 279 and 281 respectively. The cooled low-velocity exhaust fluid streams are 50 discharged from mixing section 271 into their respective exhaust fluid passageways 277 of separator-side section 257''. Exhaust fluid passageways 277 are substantially defined by partition members 273 and 274, together with the top and bottom walls of the separator-side section. A fairing 276 is attached to the trailing edge of each intake fluid discharge assembly 273, 274, and 275 on the exhaust fluid side to limit pressure losses.
- 55 60 It should also be noted that purge control apparatus including a coniform divider or throat piece mounted on a slideable control rod may be utilized in connection with exhaust ductwork downstream of peripheral exit flange 258 of separator-side section 257''. It should also be understood that the contact heat exchanger disclosed in connection with FIGS. 28, 29, 30, 31 and 32 may be constructed of any suitable material such as steel, concrete or masonry.
- 65 FIGS. 33, 34, 35, 36 and 37 embody modifications to the structure or receiver-side section 257' of the low-velocity heat exchanger disclosed in connection with FIG. 28. In these variations, configured companion

partition members 263 and 264 defining the boundaries of receiver-side nozzle passageways 266 have been replaced by straight-sided partition members 282 which define the boundaries of high-velocity intake-fluid passageways 283. In these variations, high-velocity intake fluids are supplied to intake-fluid passageways 283 from outside the heat exchanger proper.

In the variation of FIGS. 33, 34 and 35 pressurized intake fluids (air) received from exterior fan 297 at substantially constant delivery are accelerated to the maximum kinetic energy level before the contact interchange process within nozzle passageways 292 of exterior supply ductwork 284-296. The discharge of high-velocity intake fluids is channeled from exterior nozzle passageways 292 into fluid passageways 283 of receiver-side section 257' as shown.

Pressurized intake air fluids are supplied to entrance flange 284 of rotary supply ductwork 284-296 by exterior fan member 297 at substantially constant delivery. The pressurized intake fluid stream is divided by partition-type flow divider 286 within supply ductwork 284-296 into plural streams which flow into similar converging nozzle passageways 292. The near converging nozzle passageway 292 discharges to near high-velocity supply duct 295 communicating with near intake-fluid entrance duct 260 of integral ducting chamber 257. The far converging nozzle passageway 292 discharges to far high-velocity supply duct 293 communicating with far intake-fluid entrance duct 262 of integral ducting chamber 257.

The near intake-fluid supply duct branch is defined by front plate member 285 and rear configured plate member 289, together with segments of left-and-right configured plate members 290 and 291 respectively. The near intake-fluid supply duct branch exit flange 296 communicates with entrance flange 259 of near intake-fluid entrance duct 260 discharging to receiver-side section 257'.

The far intake-fluid supply duct branch is defined by front configured plate member 288 and rear plate member 287, together with segments of left-and-right configured plate members 290 and 291 respectively. The far intake-fluid supply duct exit flange 294 communicates with entrance flange 261 of far intake-fluid entrance duct 262 discharging to receiver-side section 257'.

High-velocity intake fluids enter fluid passageways 283 of receiver-side section 257' from exterior intake-fluid supply ductwork 284-296. The high-velocity intake-fluid streams are discharged as elongate fluid jets into fluid passage regions 270 of mixing section 271 (shown in phantom) and into contact interchange with adjacent elongate hot low-velocity exhaust cooling fluid streams within fluid passage regions 269. The contact interchange process then proceeds within the mixing section as described earlier, followed by inertial separation and discharge from separator-side section 257''.

The variation of FIGS. 36 and 37 should be taken together with FIGS. 33, 34 and 35. In the variation of FIGS. 36 and 37 exterior supply ductwork 298-309 inclusive and rotary fan 310 are directly exchangeable for the exterior supply ductwork 284-296 and the substantially constant-delivery fan 297 of FIGS. 33 and 35. Rotary fan 310 accelerates intake fluids (air) to the maximum kinetic energy level before the contact interchange process. Rotary fan 310 supplies high-velocity intake fluids directly to intake-fluid passageways 283 of

receiver-side section 257' by way of exterior supply ductwork 298-309.

High-velocity intake air fluids from the discharge of rotary fan 310 proceed through inlet flange 298 into the entrance plenum of exterior supply ductwork 298-309. The high-velocity intake-fluid stream is divided by partition-type flow divider 300 within exterior supply ductwork 298-309 into plural streams which flow into near high-velocity supply duct branch 308 and far high-velocity supply duct branch 306.

The near high-velocity supply duct branch 308 is defined by configured front plate member 299 and configured rear plate member 303, together with segments of side plate members 304 and 305 respectively. The near intake-fluid supply duct branch exit flange 309 communicates with entrance flange 259 of near intake-fluid entrance duct 260 of receiver-side section 257'.

The far high-velocity supply duct branch 306 is defined by configured front plate member 302 and configured rear plate member 301, together with segments of side plate members 304 and 305 respectively. The far intake-fluid supply duct branch exit flange 307 communicates with entrance flange 261 of far intake-fluid entrance duct 262 discharging to receiver-side section 257'.

High-velocity intake fluids enter fluid passageways 283 of receiver-side section 257' from exterior supply duct branches 308 and 306. The high-velocity intake-fluid streams are discharged into contact interchange with adjacent hot low-velocity exhaust cooling fluid streams within mixing section 271 as described earlier in connection with FIG. 34.

From the foregoing, it will be perceived that the present invention provides an efficient means of effecting a substantial recovery of thermal energy present in the exhaust fluid stream of an atmospheric gas turbine power plant. Variation of the gas turbine power plant process arrangement to confine the combustion processes to the turbine exhaust stream, in conjunction with use of the regenerative apparatus of the invention for heating the intake fluid stream to the gas turbine, will alleviate the fouling of turbine blade surfaces by deposit of solid products resulting from the combustion process, through segregation of the combustion process from the thermodynamic expansion process within the gas turbine.

In addition, variations in design arrangements to facilitate the contact interchange principle described in connection with the present invention may be utilized to adapt the apparatus of the invention to other heat transfer processes and systems; wherein it is desired to exchange thermal energy between fluid streams at substantially different initial pressures.

While I have shown and described certain specific embodiments of the present invention, it will be readily understood by those skilled in the art that I do not wish to be limited exactly thereto, since various modifications may be made without departing from the scope of the invention as defined in the appended claims.

I claim:

1. A non-reversing single-pass fluid-to-fluid contact heat exchanger adapted to receive and exchange energy between a plurality of fluid streams at different thermodynamic energy states in parallel flow with respect to each other; said contact heat exchanger comprising a substantially closed plenum or ducting chamber defined by side and confining walls and providing

receiver-side, mixing and separator-side sections, said mixing section disposed in said ducting chamber between the receiver-side and separator-side sections thereof; intake and exhaust-fluid passageways disposed within both the aforesaid receiver-side and separator-side ducting chamber sections, the boundaries of the said intake and exhaust-fluid passageways being defined by the interior walls of said ducting chamber and the surfaces of annular internal fluid flow control members of substantially lesser cross section than and disposed centrally of both their respective receiver-side and separator-side sections; an intake-fluid supply pipe(s) or duct(s) in communication with the receiver-side intake-fluid passageway(s), and supplying intake fluids thereto; and exhaust-fluid supply pipe(s) or duct(s) in communication with the receiver-side exhaust-fluid passageway(s) and supplying hot, low-pressure exhaust fluids thereto; an intake-fluid discharge pipe(s) or duct(s) in communication with the separator-side intake fluid passageway(s) and receiving heated intake fluids therefrom; and an exhaust-fluid discharge pipe(s) or duct(s) in communication with the separator-side exhaust-fluid passageway(s) and receiving cooled exhaust fluids therefrom; whereby particles of the aforesaid intake-fluid and exhaust-fluid streams are brought into physical contact with each other within said mixing section at substantially equal pressures while possessing substantially unequal and parallel velocity vectors so as to facilitate the contact interchange of thermal and kinetic energy therebetween, followed by a re-separation of the aforesaid intake and exhaust-fluid streams within the separator-side section of said contact heat exchanger after the contact interchange process has been substantially completed.

2. A non-reversing single-pass fluid-to-fluid contact heat exchanger adapted to receive and exchange energy between a plurality of fluid streams at different thermodynamic energy states in parallel flow with respect to each other; said contact heat exchanger comprising a substantially closed plenum or ducting chamber defined by side and confining walls and providing receiver-side, mixing and separator-side sections, said mixing section disposed in said ducting chamber between the receiver-side and separator-side sections thereof; an annular nozzle member of substantially lesser cross section than and disposed centrally of said receiver-side section whose outer surfaces and the walls of the receiver-side section define an annular intake-fluid nozzle passageway discharging to said mixing section, and whose inner surfaces define an exhaust-fluid passageway discharging to said mixing section; an intake-fluid supply pipe or duct in communication with the annular enveloping intake-fluid nozzle passageway of the receiver-side section and supplying compressed intake fluids thereto; an exhaust-fluid supply pipe or duct in communication with the central exhaust-fluid passageway of the receiver-side section and supplying hot, low-pressure exhaust fluids thereto; whereby particles of the aforesaid intake-fluid and exhaust-fluid streams are brought into physical contact with each other within said mixing section at substantially equal pressures while possessing substantially unequal and parallel and velocity vectors so as to facilitate the contact interchange of thermal and kinetic energy therebetween; an annular discharge member of substantially lesser cross section than and disposed centrally of said separator-side section whose outer sur-

faces and the walls of the separator-side section define an annular intake-fluid discharge passageway receiving heated intake fluids from said mixing section, and whose inner surfaces define an exhaust-fluid discharge passageway receiving cooled exhaust fluids from said mixing section, whereby the leading edge of said annular discharge member serves as a flow divider to separate the intake-fluid and exhaust-fluid streams from each other after the contact interchange process as flows proceeds from the mixing section into said separator-side section; an intake-fluid discharge pipe or duct in communication with the annular enveloping intake-fluid discharge passageway of the separator-side section and receiving heated intake fluid therefrom; and an exhaust-fluid discharge pipe or duct in communication with the central exhaust-fluid discharge passageway of the separator-side section whereby cooled exhaust fluids may be discharged from the apparatus of the invention.

3. The non-reversing single-pass fluid-to-fluid contact heat exchanger of claim 2 wherein the annular nozzle member is disposed coaxially with the receiver-side section along the flow axis thereof.

4. The non-reversing single-pass fluid-to-fluid contact heat exchanger of claim 2 wherein the annular discharge member is disposed coaxially with the separator-side section along the flow axis thereof.

5. The non-reversing single-pass fluid-to-fluid contact heat exchanger of claim 2 wherein a coniform flow divider is disposed axially of an exhaust-fluid discharge aperture supplied by the said central exhaust-fluid discharge passageway of the separator-side section and directed against the discharge of cooled exhaust fluids therefrom, and means for axially advancing and retracting the said coniform flow divider with respect to the said exhaust-fluid discharge aperture.

6. A non-reversing single-pass fluid-to-fluid contact heat exchanger adapted to receive and exchange energy between a plurality of fluid streams at different thermodynamic energy states in parallel flow with respect to each other; said contact heat exchanger comprising a substantially closed plenum or ducting chamber defined by side and confining walls and providing receiver-side, mixing and separator-side sections, said mixing section disposed in said ducting chamber between the receiver-side and separator-side sections thereof; an annular nozzle member of substantially lesser cross section than and disposed centrally of said receiver-side section whose inner surfaces define a central intake-fluid nozzle passageway discharging to said mixing section, and whose outer surfaces and the walls of the receiver-side section define an annular exhaust-fluid passageway discharging to said mixing section; an intake-fluid supply pipe or duct in communication with the central intake-fluid nozzle passageway of the receiver-side section and supplying compressed intake fluids thereto; an exhaust-fluid supply pipe or duct in communication with the annular enveloping exhaust-fluid passageway of the receiver-side section and supplying hot, low-pressure exhaust fluids thereto; whereby particles of the aforesaid intake-fluid and exhaust-fluid streams are brought into physical contact with each other within said mixing section at substantially equal pressures while possessing substantially unequal and parallel and velocity vectors so as to facilitate the contact interchange of thermal and kinetic energy therebetween; an annular discharge member of

substantially lesser cross section than and disposed centrally of said separator-side section whose inner surfaces define a central intake-fluid discharge passageway receiving heated intake fluids from said mixing section, and whose outer surfaces and the walls of the separator-side section define an annular exhaust-fluid discharge passageway receiving cooled exhaust fluids from said mixing section, whereby the leading edge of said annular discharge member serves as a flow divider to separate the intake-fluid and exhaust-fluid streams from each other after the contact interchange process as flow proceeds from the mixing section into said separator-side section; an intake-fluid discharge pipe or duct in communication with the central intake-fluid discharge passageway of the separator-side section and receiving heated intake fluids therefrom; and an exhaust-fluid discharge pipe or duct in communication with the annular enveloping exhaust-fluid discharge passageway of the separator-side section whereby cooled exhaust fluids may be discharged from the apparatus of the invention.

7. The non-reversing single-pass fluid-to-fluid contact heat exchanger of claim 6 wherein the annular nozzle member is disposed coaxially with the receiver-side section along the flow axis thereof.

8. The non-reversing single-pass fluid-to-fluid contact heat exchanger of claim 6 wherein the annular discharge member is disposed coaxially with the separator-side section along the flow axis thereof.

9. The non-reversing single-pass fluid-to-fluid contact heat exchanger of claim 6 wherein a conform flow divider is disposed axially of an exhaust-fluid discharge aperture supplied by the said annular enveloping exhaust-fluid discharge passageway and directed against the discharge of cooled exhaust fluids therefrom, and means for axially advancing and retracting the said conform flow divider with respect to the said exhaust-fluid discharge aperture.

10. The non-reversing single-pass fluid-to-fluid contact heat exchanger of claim 6 wherein a plurality of receiver-side nozzle members are disposed within the receiver-side section opposite a plurality of companion separator-side discharge members disposed within the separator-side section of said ducting chamber.

11. The non-reversing single-pass fluid-to-fluid contact heat exchanger of claim 2 wherein the annular nozzle member and exhaust-fluid supply pipe of the receiver-side section are slidably disposed along the flow axis thereof; and means for axially advancing or retracting said receiver-side annular nozzle member with respect to the leading edge of its companion opposite separator-side annular discharge member along the longitudinal flow axis of said contact heat exchanger.

12. The non-reversing single-pass fluid-to-fluid contact heat exchanger of claim 2 wherein the annular discharge member and exhaust-fluid discharge pipe of the separator-side section are slidably disposed along the flow axis thereof; and means for axially advancing or retracting said separator-side annular-discharge member with respect to the trailing edge of its companion opposite receiver-side annular nozzle member along the longitudinal flow axis of said contact heat exchanger.

13. The non-reversing single-pass fluid-to-fluid contact heat exchanger of claim 6 wherein the annular nozzle member and intake-fluid supply pipe of the re-

ceiver-side section are slidably disposed along the flow axis thereof; and means for axially advancing or retracting said receiver-side annular nozzle member with respect to the leading edge of its companion opposite separator-side annular discharge member along the longitudinal flow axis of said contact heat exchanger.

14. The non-reversing single-pass fluid-to-fluid contact heat exchanger of claim 6 wherein the annular discharge member and intake-fluid discharge pipe of the separator-side section are slidably disposed along the flow axis thereof; and means for axially advancing or retracting said separator-side annular discharge member with respect to the trailing edge of its companion opposite receiver-side annular nozzle member along the longitudinal flow axis of said contact heat exchanger.

15. The non-reversing single-pass fluid-to-fluid contact heat exchanger of claim 6 wherein a plurality of receiver-side annular nozzle members and attached intake-fluid supply pipes are slidably disposed within the receiver-side section along the flow axes thereof; and means for axially advancing and retracting said plurality of receiver-side annular nozzle members with respect to the leading edges of their respective individual opposite companion members of a plurality of separator-side annular discharge members along the longitudinal flow axes of said contact heat exchanger.

16. The non-reversing single-pass fluid-to-fluid contact heat exchanger of claim 6 wherein a plurality of separator-side annular discharge members and attached intake-fluid discharge pipes are slidably disposed within the separator-side section along the flow axes thereof; and means for axially advancing and retracting said plurality of separator-side annular discharge members with respect to the trailing edges of their respective individual opposite companion members of a plurality of receiver-side annular nozzle members along the longitudinal flow axes of said contact heat exchanger.

17. The non-reversing single-pass fluid-to-fluid contact heat exchanger of claim 2 wherein the elongate plenum or ducting chamber provides a slidable connection in the mid-body thereof which permits either of the receiver-side or separator-side sections to telescope into the other along the flow axis of the heat exchanger, and means for axially advancing or retracting either of the aforesaid receiver-side or separator-side sections to adjust characteristic length of the heat transfer process between the trailing edge of the receiver-side annular nozzle member and the leading edge of the separator-side annular discharge member.

18. The non-reversing single-pass fluid-to-fluid contact heat exchanger of claim 6 wherein the elongate plenum or ducting chamber provides a slidable connection in the mid-body thereof which permits either of the receiver-side or separator-side sections to telescope into the other along the flow axis of the heat exchanger, and means for axially advancing or retracting either of the aforesaid receiver-side or separator-side sections to adjust characteristic length of the heat transfer process between the trailing edge of the receiver-side annular nozzle member and the leading edge of the separator-side annular discharge member.

19. The non-reversing single-pass fluid-to-fluid contact heat exchanger of claim 6 wherein a plurality of receiver-side nozzle members are disposed within the receiver-side section opposite a plurality of com-

panion discharge members disposed within the separator-side section, whereby the elongate plenum or ducting chamber provides a slidable connection in the mid-body thereof which permits either of the receiver-side or separator-side sections to telescope into the other along the slow axes of the heat exchanger, and means for axially advancing or retracting either of the aforesaid receiver-side or separator-side sections to adjust characteristic length of the heat transfer process between the trailing edges of the plurality of receiver-side annular nozzle members and the leading edges of the plurality of separator-side annular discharge members.

20. A non-reversing single-pass fluid-to-fluid contact heat exchanger adapted to receive and exchange energy between a plurality of fluid streams at different thermodynamic energy states in parallel flow with respect to each other; said contact heat exchanger comprising a substantially closed plenum or ducting chamber defined by side and confining walls and providing receiver-side, mixing and separator-side sections, said mixing section disposed in said ducting chamber between the receiver-side and separator-side sections thereof; a plurality of intake-fluid nozzles each formed by configured companion partition members disposed laterally between the sidewalls of said receiver-side section in spaced proximity with respect to each other and adjacent partition members and the said sidewalls so that interstices formed therebetween divide the receiver-side section into alternate adjacent intake-fluid nozzle passageways and exhaust-fluid passageways which discharge to the mixing section of said heat exchanger; intake-fluid supply conduits communicating with the nozzle passageways of said receiver-side section and supplying cool pressurized intake fluids thereto; exhaust-fluid supply conduits communicating with the exhaust-fluid passageways of said receiver-side section and supplying hot low-pressure exhaust fluids thereto; whereby particles of the aforesaid intake-fluid and exhaust-fluid streams are brought into physical contact with each other within said mixing section at substantially equal pressures while possessing substantially unequal and parallel and velocity vectors so as to facilitate the contact interchange of thermal and kinetic energy therebetween; a plurality of intake-fluid discharge members each formed by flow-dividing companion partition members disposed laterally between the sidewalls of said separator-side section in spaced proximity with respect to each other and adjacent companion partition members and the said sidewalls so that interstices formed therebetween divide the separator-side section into alternate adjacent intake-fluid and exhaust-fluid passageways disposed opposite their respective companion intake-fluid and exhaust-fluid passageways of the receiver-side section; whereby the contacting intake-fluid and exhaust-fluid streams leaving the said mixing section may enter their respective intake-fluid and exhaust-fluid passageways of the separator-side section and flow towards discharge outlets of said contact heat exchanger; intake-fluid discharge conduits communicating with the intake-fluid discharge passageways of said separator-side section and receiving heated intake fluids therefrom; and exhaust-fluid discharge conduits communicating with the exhaust-fluid discharge passageways of said separator-side section and receiving cooled exhaust fluids therefrom.

21. The non-reversing single-pass fluid-to-fluid contact heat exchanger of claim 20 wherein the receiv-

er-side partition members define a single nozzle passage disposed centrally with the central longitudinal flow plane of the heat exchanger.

22. The non-reversing single-pass fluid-to-fluid contact heat exchanger of claim 20 wherein the separator-side partition members define a single intake-fluid discharge passageway disposed centrally with the central longitudinal flow plane of the heat exchanger.

23. A non-reversing single-pass fluid-to-fluid contact heat exchanger adapted to receive and exchange energy between a plurality of fluid streams at different thermodynamic energy states in parallel flow with respect to each other; said contact heat exchanger comprising a substantially closed plenum or ducting chamber defined by side and confining walls and providing receiver-side, mixing and separator-side sections, said mixing section disposed in said ducting chamber between the receiver-side and separator-side sections thereof; a plurality of partition members having spaced 10 proximity with respect to each other and the sidewalls of said receiver-side section and disposed laterally between the said sidewalls so that interstices formed therebetween divide the receiver-side section into alternate adjacent intake-fluid and exhaust-fluid passageways which discharge to the mixing section of said heat exchanger; a fluid pump or fan disposed to supply pressurized intake fluids; intake-fluid supply conduits communicating with the discharge of said fluid pump or fan and the individual intake-fluid passageways of the said receiver-side section; an intake-fluid nozzle passageway disposed in the supply conduit branch for each individual intake-fluid passageway of the said receiver-side section and discharging high-velocity intake fluids thereto; exhaust-fluid supply conduits communicating 20 with the exhaust-fluid passageways of said receiver-side section and supplying hot low-velocity exhaust fluids thereto; whereby particles of the aforesaid intake-fluid and exhaust-fluid streams are brought into physical contact with each other within said mixing section at substantially equal pressures while possessing substantially unequal and parallel velocity vectors so as to facilitate the contact interchange of thermal and kinetic energy therebetween; a plurality of flow-dividing partition members having spaced proximity with respect to each other and the sidewalls of said separator-side section and disposed laterally between the said sidewalls so that interstices formed therebetween divide the separator-side section into alternate adjacent intake-fluid and exhaust-fluid passageways disposed opposite 30 their respective companion intake-fluid and exhaust-fluid passageways of the receiver-side section; whereby the contacting intake-fluid and exhaust-fluid streams leaving the said mixing section may enter intake-fluid discharge conduits communicating with the intake-fluid discharge passageways of said separator-side section and receiving heated intake fluids therefrom; and exhaust-fluid discharge conduits communicating with the exhaust-fluid discharge passageways of said separator-side section and receiving cooled exhaust fluids therefrom.

24. A non-reversing single-pass fluid-to-fluid contact heat exchanger adapted to receive and exchange energy between a plurality of fluid streams at different thermodynamic energy states in parallel flow with respect to each other; said contact heat exchanger comprising a substantially closed plenum or ducting chamber defined by side and confining walls and providing

receiver-side, mixing and separator-side sections, said mixing section disposed in said ducting chamber between the receiver-side and separator-side sections thereof; a plurality of partition members having spaced proximity with respect to each other and the sidewalls of said receiver-side section and disposed laterally between the said sidewalls so that interstices formed therebetween divide the receiver-side section into alternate adjacent intake-fluid and exhaust-fluid passageways which discharge to the mixing section of said heat exchanger; a fluid pump or fan disposed to supply high-velocity intake fluids; intake-fluid supply conduits communicating with the discharge of said fluid pump or fan and the individual intake-fluid passageways of the said receiver-side section; exhaust-fluid supply conduits communicating with the exhaust-fluid passageways of said receiver-side section and supplying hot low-velocity exhaust fluids thereto; whereby particles of the aforesaid intake-fluid and exhaust-fluid streams are brought into physical contact with each other within said mixing section at substantially equal pressures while possessing substantially unequal and parallel velocity vectors so as to facilitate the contact interchange of thermal and kinetic energy therebetween; a plurality of flow-dividing partition members having spaced proximity with respect to each other and the sidewalls of said separator-side section and disposed laterally between the said sidewalls so that interstices formed therebetween divide the separator-side section into alternate adjacent intake-fluid and exhaust-fluid passageways disposed opposite their respective companion intake-fluid and exhaust-fluid passageways of the receiver-side section; whereby the contacting intake-fluid and exhaust-fluid streams leaving the said mixing sec-

tion may enter their respective intake-fluid and exhaust-fluid passageways of the separator-side section and flow towards discharge outlets of said contact heat exchanger; intake-fluid discharge conduits communicating with the intake-fluid discharge passageways of said separator-side section and receiving heated intake-fluids therefrom; and exhaust-fluid discharge conduits communicating with the exhaust-fluid discharge passageways of said separator-side section and receiving cooled exhaust fluids therefrom.

25. The non-reversing single-pass fluid-to-fluid contact heat exchanger of claim 2 wherein a coniform flow divider is disposed axially of a duct throat section within the intake-fluid discharge ductwork of said contact heat exchanger and supplied from the said annular intake-fluid discharge passageway of the separator-side section, the said coniform flow divider being directed against the discharge of heated intake fluids therefrom, and means for axially advancing and retracting the said coniform flow divider with respect to the said intake-fluid discharge throat section.

26. The non-reversing single-pass fluid-to-fluid contact heat exchanger of claim 6 wherein a coniform flow divider is disposed axially of a duct throat section within the intake-fluid discharge ductwork of said contact heat exchanger and supplied from the said central intake-fluid discharge passageway of the separator-side section, the said coniform flow divider being directed against the discharge of heated intake fluids therefrom, and means for axially advancing and retracting the said coniform flow divider respect to the said intake-fluid discharge throat section.
